UNITED STATES PATENT OFFICE.

FREDERIC L. WHEELER, OF BERKELEY, CALIFORNIA.

DESIGN FOR A STATUETTE.

49,103.

Specification for Design. Patented May 23, 1916.

Application filed April 14, 1915. Serial No. 21,473. Term of patent 3½ years.

To all whom it may concern:

Be it known that I, FREDERIC L. WHEELER, a citizen of the United States, residing at Berkeley, in the county of Alameda, State of California, have invented a new, original, and ornamental Design for Statuettes, of which the following is a specification, reference being had to the accompanying drawing, forming part hereof.

The figure is a perspective view from in front of a statuette, showing my new design.

What I claim and desire to secure by Letters Patent is:—

The ornamental design for a statuette as shown.

In testimony whereof, I have hereunto set my hand this 8th day of April, 1915.

FREDERIC L. WHEELER.
